C. ANDRADE, JR

BED SHEET

Filed Nov. 30, 1927

FIG. 1

FIG. 2

FIG. 3

INVENTOR

Cipriano Andrade, Jr

UNITED STATES PATENT OFFICE.

CIPRIANO ANDRADE, JR., OF NEW YORK, N. Y.

BED SHEET.

Application filed November 30, 1927. Serial No. 236,658.

My invention relates to a bed sheet adapted to fully surround the neck or head of a sleeper in a bed, thus helping to prevent any coldness or catching cold or noise.

5 I attain this object by the mechanism illustrated in the accompanying drawings, in which:

Fig. 1 is a top view of the upper part of my device before it is assembled; Fig. 2 is 10 a top view of the lower part of my device before it is assembled; and Fig. 3 is a top view of my complete device when assembled.

Similar letters and numerals refer to similar parts throughout the several views:

A is the upper part of my device made of any desired material for a bed sheet. A¹ is the upper end of element A. A² is the lower end of element A. A⁴ are the side ends of element A. B is the lower part of my device made of any desired material for a bed sheet, said element A being substantially longer in side length than the side length of element B. B² is the upper end of element B. B³ is the lower end of element B. B⁴ are the side ends of element B.

The operation of my device is as follows:

My device will only be used as a top cover bed sheet. And parts A² and B² hereof are 30 located over the top of the neck of the sleeper. For a double bed, the side length of A can be about 14½ feet, and the end length thereof a little over 3 feet; and the side length of B can be about 8 feet, and the end length of B can be about 7 feet. This part A² then should have its entire full length gathered and fastened permanently onto the entire full length of part B² as shown in Fig. 3 to provide a fullness in the edge A¹.

40 The result of this is that the part A, because of its large extra gathered length all through it, can not only cover the neck, and if desired also the head of either one or two sleepers in the bed, but in addition thereto either one or both of the sleepers can pull part A completely around their neck and if desired also completely around their head and so remain all through their sleep; and when this is done it will not pull the side 45 ends of part B² inward, the reason being that the part A, A¹ and A² is so much longer

than the length of part B². This makes it impossible for any cold air to get into the neck or head of the sleeper. In addition thereto, when the sleeper's window is open, 55 if part A is put completely around the head of the sleeper, or only over the ears, it largely minimizes for the sleeper the noise which is becoming greater and greater in all the 60 cities of this nation by the running and tooting of taxicabs, busses, trucks and private cars all through the night.

It will of course be understood that my device is not limited to a double bed, but can be used on a single bed, or on any bed larger 65 than a double bed, and the various dimensions herein mentioned can of course be changed to anything larger or smaller as desired. The form of my device shown in Fig. 3 hereof is the most efficient, because when 70 element A is gathered and fastened to element B as therein shown, element A at any portion thereof has much extra gathered side length to cover the neck or head of the sleeper, without pulling in the side ends of 75 element B.

I claim:

1. In a top cover bed sheet; a lower top part of material all of full width to cover both sides of the bed, and to be fastened under the bottom of the bed on both sides thereof, the upper end of said lower top part of material being entirely straight; and an upper top part of material, the upper end and the lower end thereof each being substantially longer than the upper end of said lower top part of material, said lower end of said upper top part of material having its full length gathered and all fastened to the full length of the upper end of the lower top part of material.

2. In a top cover bed sheet; a lower top part of material, with an upper end; an upper top part of material, the upper end and the lower end thereof each being substantially longer than the upper end of said lower top part of material, said lower end of said upper top part of material being gathered and fastened to the upper end of the lower top part of material.

CIPRIANO ANDRADE, JR.
